Del Moral et al., US Appl. No. 29/675,949 filed Jan. 7, 2019, "Wallet for Mobile Device or Mobile Device Case."

(Continued)

Primary Examiner — Mojtaba Tehrani(74) *Attorney, Agent, or Firm* — Lerner David LLP(57) **CLAIM**

The ornamental design for a WALLET FOR MOBILE DEVICE, as shown and described.

DESCRIPTION

FIG. 1 is a front perspective view of a WALLET FOR MOBILE DEVICE showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and

FIG. 7 is a bottom plan view thereof.

The broken lines shown in the drawings are for the purpose of illustrating environmental structure and form no part of the claimed design.
